UNITED STATES PATENT OFFICE.

CHARLES BURDICK, OF ERIE, PENNSYLVANIA, ASSIGNOR TO O. F. MERWIN, OF ERIE, PENNSYLVANIA, DOING BUSINESS AS MERWIN MANUFACTURING COMPANY.

WIRE-CUTTING DEVICE.

No. 889,177.

Specification of Letters Patent. Patented May 26, 1908.

Application filed June 22, 1907. Serial No. 380,254.

To all whom it may concern:

Be it known that I, CHARLES BURDICK, a citizen of the United States, residing at Erie, in the county of Erie and State of Pennsylvania, have invented new and useful Improvements in Wire-Cutting Devices, of which the following is a specification.

This invention relates to wire cutting devices and consists of certain improvements in the construction thereof as will hereinafter be fully described and pointed out in the claims.

The invention is illustrated in the accompanying drawing as follows:

Figure 1 is a plan view. Fig. 2 an elevation of the same. Fig. 3 is a section on the line 3—3 in Fig. 2.

The invention is shown as applied to the shanks of tinner's shears.

1—1 marks the blades of the shears which are pivoted on the pin 2, and 3—3 the shanks of the shears. A gear segment 4 is arranged on the end one of the shanks and a gear segment 5 is pivoted on the other shank. Gear segments 4 and 5 are in mesh. The gear 5 may be operated by a lever 7.

It will readily be seen as the gear segment 5 is operated it acts upon gear segment 4 to give relative movement to the shanks 3 so that the shears may be operated with any desired leverage. This part of the construction is not novel.

Arranged in each shank equally distant

from the pivot of the shanks are circular openings 8. These are ordinarily formed by simply drilling through the two shanks after they are assembled. Dies 9 are inserted in these openings. These dies are provided with a plurality of cutting openings 10 of different sizes, the openings of the same size in the two dies being in register with the shanks in one position so that a wire 11 may be passed through them and cut off by the relative movement of the shanks. The dies are held in place by the set screws 12. By making both dies round and supplying each shank with such a die a plurality of openings may be readily supplied and different sizes of wire may be advantageously cut without adjustment of the dies.

What I claim as new is:

The combination of the shanks 3, pivotally secured together and having the circular openings 8 concentrically arranged with relation to the pivots of the shanks; and the dies 9 seated therein, having corresponding cutting holes of different sizes correspondingly arranged in said dies.

In testimony whereof I have hereunto set my hand in the presence of two subscribing witnesses.

CHARLES BURDICK.
